UNITED STATES PATENT OFFICE.

VETAL BÉSSIER, OF NEW YORK, N. Y., ASSIGNOR OF ONE-HALF TO HENRY A. ROBBINS, OF WASHINGTON, DISTRICT OF COLUMBIA.

FIRE-ESCAPE.

SPECIFICATION forming part of Letters Patent No. 295,477, dated March 18, 1884.

Application filed December 20, 1883. (No model.)

To all whom it may concern:

Be it known that I, VETAL BÉSSIER, of the city, county, and State of New York, have invented an Improved Fire-Escape; and I do hereby declare that the following is a full and exact description thereof, reference being had to the accompanying drawings, making part of this specification.

My invention belongs to the class of ladder-escapes and to the sub-class of folding ladders, and the ladder is especially adapted to the balconies of buildings, or to platforms or landings on buildings serving a similar purpose.

One feature of my invention is the ladder folded closely into a frame, so that the ladder and frame form a complete door, which fills the hatchway of the balcony, being hinged to or at one side thereof, whereby the upper end of the ladder is constantly supported, and when the door is unfastened in the hatchway the ladder descends by its own weight till it reaches the next lower balcony or the ground.

Another feature of invention consists in the peculiar construction of the folding ladder, adapting it to be folded into the frame.

Other points of invention consist in the means for letting down each ladder by operating a mechanism from the outside of the building near the ground, and from positions inside of the building; also, in the connection of an alarm with the said mechanism.

In the accompanying drawings, Figure 1 represents the front of a house or building provided with my improved folding ladders applied to the balconies thereof; Fig. 2, a vertical section of the front of the building from front to rear, showing the ladders applied thereto; Fig. 3, a partial horizontal section of the building-wall and top view of one of the balconies containing the ladder folded therein as a door; Figs. 4 and 5, views showing the construction of the folding ladder; Figs. 6 and 7, views showing a modified construction of the folding ladder; Figs. 8 and 9, views showing another modification of the construction of the folding ladder; Figs. 10 and 11, views of the ladder-frame; Fig. 12, a view showing means for holding up and letting down the ladder; Fig. 13, a view showing an alarm attachment and means for connect-

ing it with the means for letting down the ladder or ladders.

Like letters designate corresponding parts in all of the figures.

I have represented in the accompanying drawings simple means for carrying out all the features of my invention. I show the front of a three-story house, the second and third stories being respectively provided with balconies A. B. A folding ladder, C, is shown located in the lower balcony, for descending from the said balcony to the ground, and a folding ladder, D, connected with the upper balcony, for descending from that balcony to the lower balcony. For clearness of illustration, I have shown the upper ladder let down for use, and the lower ladder folded up and locked in the hatchway of the balcony-floor; but it is to be understood that all the ladders of the building are or may be held up at the same time and let down simultaneously.

In the description of the invention I will first specify the peculiar construction of the ladder itself. The essential feature of this invention is the combination of a series of rounds or "rungs," a a, and a series of connecting links or rods, b b, pivoted to the ends of the rounds and together in pairs, and adapted to be folded entirely behind or within the rounds, so that when the rounds and links are thus folded together, they occupy no more room in the longitudinal direction of the ladder than the simple aggregate widths of the rounds, which, thus being arranged closely side by side and held in a frame, E, form a close trap-door, filling the hatchway in the balcony-floor, as shown in Fig. 3. Thereby a safe and unobjectionable continuation of the balcony-floor is formed, and the door itself and the hatchway are made as small as practicable.

In the specific construction of the ladder to produce the effect above set forth various means or modifications thereof may be adopted. I will describe two or three modes of construction. Thus, according to the construction shown in Figs. 4 and 5, each round is formed of two metallic plates, a a, one in front of the other, and the ends of the contiguous links above and below the round at each

end thereof are lapped one over the other and between the ends of the round-plates, so that a single pivot-pin, *c*, is passed through all the four parts, leaving sufficient width of space 5 between the front and back plates of the round for the two links to fold in between them, as shown in Fig. 5. This is the same at each end of the round. Then the upper link of one round and the lower link of the round 10 above are lapped over each other and connected by a pivot, *d*, and this also at each end of the round, as shown; and in order that the links may fold entirely behind the front round-plate, the two connected links at one end of 15 the round must not extend beyond the middle of each round, in order not to quite meet the links at the other end of the rounds. Thus it will be observed that the distance between the rounds, when the ladder is unfolded, is practically a little less, and might be much less, 20 than the length of the several rounds. There may be a stay-bolt, *e*, connecting the middle of each pair of plates *a a*, composing each round, to keep them firmly in proper relative positions 25 and at a proper distance from each other. The rounds and connecting-links may be made of metallic plates, and may be quite thin and light, especially when made of sheet-steel. A somewhat lighter construction is shown in 30 Figs. 6 and 7. Here a single plate *a* forms each round. The links *b b* are the same as in Figs. 4 and 5, and the manner of pivoting them together and to the rounds is the same as described for the construction shown in 35 those figures. In Figs. 8 and 9 I also show single-plate rounds *a a*, but double-plate links *b b* alternate with single-plate links, as shown. The mode of pivoting together and to the rounds is the same as above described. 40 Now, as to the ladder-frame *E*, (shown in Figs. 3, 10, and 11,) it is composed of three sides, *f g g*, which may most conveniently be formed of a single bar of metal bent to form three sides of a rectangle, as shown. One, or 45 preferably two, cross-bars, *h h*, are secured to the frame next to the middle side, *f*, corresponding to or forming one round of the ladder, and from this the remainder of the ladder is suspended. When the rounds are formed 50 of two plates, as shown in Figs. 4 and 5, they project a little beyond the links *b b* at the ends, so as to embrace longitudinal ribs *i i*, secured to or formed with the sides *g g* of the frame, as shown in Fig. 10, and by this means 55 the ends of all the rounds are retained and supported in the frame when the latter is in a horizontal position in the hatchway, but ready to slide out of the frame when the said frame is swung down from the hatchway. When 60 single plates *a a* are used to form the ladder-rounds, there are grooves or ways *i i* in the inner surface of the sides *g g* of the frame, as shown in Fig. 11, for the projecting ends of the rounds to run and be supported in. The 65 frame *E* is hinged at one side of the hatchway, and it is best to hinge or pivot it to or at

the side next to the wall of the building, as shown in Fig. 3, for the purpose of allowing the ladder to hang down in front of and near to the wall of the building. 70

There may be employed a series of prop-arms, each succeeding lower arm being a little longer than the one above, as shown in Fig. 2, whereby the ladder is held farther from the wall at the lower than at the upper end, and gradually increases in distance from the top to the bottom. This construction renders the descent on the ladder much more convenient and safe than if the stays were all of equal length. These stays or props are conveniently made by bending back the ends of the back plates of the ladder-rounds, made long enough for the purpose, or when the rounds are made of single plates those are made long enough to be bent back and form the stays. 80 85

For securing the ladder and its frame in the hatchway of a balcony or similar floor or landing various devices may be adopted. I have shown in Fig. 12 a simple means for the purpose. The lower round of the ladder may be 90 made of a single plate bent at the lower edges to form two sides and a bottom, *k*, and in this bottom part a slot or hole, *l*, is formed. Into this slot the catch *m* of a lever, *G*, enters, to sustain that side of the combined ladder and 95 frame composing the hatchway-door. If simply two flat plates form the lower round of the ladder, the catch *m* enters between them. If a single plate forms the lower round of the ladder, the catch *m* swings under it. The lever 100 *G* is pivoted, and has a horizontal swinging movement in or under the balcony-floor for allowing its catch *m* to sustain or set free the ladder in the hatchway. With this lever (or its equivalent) any suitable mechanism or device 105 may be employed for setting free or tripping the ladder from any point or position desired. In Fig. 12 I show a rod, *H*, pivoted at *n* to the end of the lever opposite to the catch *m*, and extending thence inward in or under the balcony-floor, and through the wall to a hall or room in the building, and terminating with a knob or handle, *o*, by which to draw the rod inward for tripping the ladder. The rod may be moved outward for fastening up the ladder 110 by a counter-spring. Any desired number and arrangement of such tripping devices may be employed leading to different rooms or positions, and they may be secured in any desired way, so that they may not be unnecessarily 115 tampered with or accidentally moved. 120

One other connection with the ladders I deem to be important—namely, to reach to the lower part of a building, so as to be accessible to a fireman or other person in the street or outside 125 of the building, for letting down the ladders, in case that the inmates of the building do not or cannot let the ladders down in the event of a fire or other casualty. I have shown a means of accomplishing this in Figs. 2 and 12. The knob or pull *p*, Fig. 2, is housed in a suitable box or recess, *I*, and a rod, wire, or cord, *q*, 130

extends therefrom up to a bell-crank, *r*, pivoted to a support in such a position that the other arm of the bell-crank is connected with the rod *H*, so that pulling down on this rod, 5 wire, or cord will draw the said rod *H* inward and trip the ladder. The rod, wire, or cord *g* is, or should preferably, be connected with all the rods *H* for the several ladders, where more than one is used, or where there are three or 10 more stories in the building.

It is also desirable to connect with the ladder-tripping mechanism a bell or suitable alarm, not only to warn all inmates when the ladders are let down to escape by, but also to 15 warn them in case burglars or other improper persons tamper with the ladders. I have shown in Figs. 2 and 13 such an alarm connected with the tripping-rod *H*. From the bell-crank *r* a rod, *s*, extends upward to another bell-crank, 20 *t*, to which a horizontal rod, *u*, is pivoted. On the end of the rod *u* is a stop or catch, *v*, which holds a catch-pin, *w*, on the periphery of a pulley-wheel, *J*, on the pulley or shaft of which is wound a cord, *y*, bearing a weight, *K*. An 25 arm, *x*, on this wheel is arranged to strike the outer end of a pivoted hammer-lever, *y*, bearing a hammer, *z*, which strikes a bell, *L*, after the outer end of the hammer-lever has been depressed and then set free by the arm *x* at 30 each revolution of the wheel *J*. When the ladder is held in the hatchway of the balcony by the catch *m* of the lever *G*, the stop *v* holds against the catch-pin *w* and prevents the turning 35 of the wheel; but when the rod *H* is drawn in to trip the ladder the stop *v* is drawn away from the catch-pin *w* and allows the bell to be sounded. After the alarm has at any time been sounded, the weight-cord *y* is again wound upon the wheel pulley or shaft, ready to sound 40 another alarm. Thus I show one way of con-

necting an alarm with the ladder-tripping mechanism.

I claim as my invention—

1. A ladder, *C*, constructed to fold with its rounds side by side, and contained in a frame, 45 *E*, in combination with the hatchway of a balcony-floor or other landing, whereby the said folded ladder and its frame form a close door for the said hatchway, substantially as and for the purpose herein specified. 50

2. The combination of a closely-folding ladder, *C*, a three-sided frame, *E*, hinged at the middle side to one side of a floor-hatchway, and a catch, *m*, for sustaining the ladder, shut into the hatchway, substantially as and for the 55 purpose set forth.

3. The combination of a folding ladder, *C*, hinged in a balcony or landing hatchway, a sustaining lever or holder, *G*, and a trip rod or rods, *H*, reaching from the holder to one 60 or more positions inside of the building, substantially as and for the purpose herein specified.

4. The combination of a folding ladder, *C*, hinged in a balcony or landing hatchway, a 65 sustaining lever or holder, *G*, a trip-rod, *H*, a tripping-pull, *p*, accessible near the ground outside of the building, and mechanism connecting the said pull and trip-rod, substantially as and for the purpose set forth. 70

5. The combination of a folding ladder, *C*, hinged in a balcony or landing hatchway, a sustaining lever or holder, *G*, tripping mechanism *H*, an alarm, *L*, and mechanism connecting the alarm with the tripping mechanism, for the purpose herein specified. 75
